UNITED STATES PATENT OFFICE.

WILLIAM E. BERTRAM, OF BROOKLYN, NEW YORK, ASSIGNOR TO INTERNATIONAL TYPESETTING MACHINE COMPANY, OF NEW YORK, N. Y., A CORPORATION OF NEW YORK.

LINOTYPE-MACHINE.

1,108,828.

Specification of Letters Patent. Patented Aug. 25, 1914.

Application filed November 23, 1911. Serial No. 081,940.

To all whom it may concern:

Be it known that I, WILLIAM E. BERTRAM, a citizen of the United States, residing at Brooklyn, in the county of Kings and State of New York, have invented new and useful Improvements in Linotype-Machines, of which the following is a specification.

The present invention relates to improvements in linotype machines and particularly to the vise which clamps the assembled line of matrices and spacers preparatory to the casting operation, and the object of this invention is to provide simplified and improved means for adjusting the distance between the vise jaws whereby the vise may be set for lines of different lengths, the present invention providing means by which this result may be accomplished quickly and easily, lost motion between the operative parts is reduced to a minimum, and a very strong and rigid structure is provided whereby a strong and positive clamping action is produced upon the line by the vise jaws.

To these and other ends, the invention consists in certain improvements, and combinations and arrangements of parts, all as will be hereinafter more fully described, the novel features being pointed out particularly in the claims at the end of the specification.

In the accompanying drawing: Figure 1 is a side elevation of the inner face of the vise of a linotype machine provided with an adjustment embodying the present invention; Fig. 2 is a perspective view showing the vise jaw adjusting means on an enlarged scale; Fig. 3 represents a section on the line 3—3 of Fig. 2; and Fig. 4 is a perspective view of the spacer pin which abuts against the adjustable vise jaw.

Similar parts are designated by the same reference characters in the several views.

Linotype machines as commonly used and especially those of the Mergenthaler type employ a vise which receives and clamps the assembled lines of matrices and spacers preparatory to the casting operation, one of the vise jaws being moved or adjusted periodically to clamp and release the line. In operating linotype machines, it is necessary occasionally to adapt the machine for the production of slugs of different lengths to correspond to the lengths of the lines of the printed matter. The slugs of each size are

cast in a mold of appropriate size and in order to adapt the machine for the production of slugs of different lengths, it is necessary to correspondingly vary the distance between the vise jaws.

The present invention provides more simple and improved means for accomplishing this result, such means enabling the adjustments to be made quickly and easily and the adjusting means provided by the present invention is strong and rigid and practically free from lost motion, thereby insuring the proper clamping and releasing actions of the vise jaws with respect to the lines of matrices.

In the present instance, the improvements are shown in connection with the vise mechanism of the Mergenthaler linotype machine as commonly used, 1 designating a portion of the machine frame which supports the relatively stationary vise jaw 2 and the slideable or movable vise jaw 3. The adjusting mechanism embodying the present invention cooperates in the present instance with the relatively movable or adjustable jaw 3, it being understood that this jaw moves periodically in a direction toward the jaw 2 to clamp an assembled line of matrices and spacers and recedes from the jaw 2 to release the line of matrices and spacers. In the construction shown, a bracket 4 is fixed to the frame 1 and this bracket is provided with a bearing or guide 5. The vise adjusting member 6 passes through the bearing or guide 5 and is capable of rotating therein and it is also capable of a longitudinal or axial adjustment in this bearing or guide. The adjusting member in the present instance is in the form of a rod one end of which is threaded to form a screw 7. This screw is threaded into a nut or abutment 8 which is guided to slide toward and from the vise under the influence of the screw 7, rotary motion of the abutment being prevented. The abutment has a boss 9 to receive a shouldered pin 10, the boss being provided with a socket for this purpose, and the corresponding end of the pin 10 is preferably reduced, as shown, and split to form somewhat resilient tongues 11 which will produce sufficient friction to prevent displacement of the pin. This pin may either engage the outer end of the adjustable vise jaw 3 or it may have a cap 12 fitted on its operative end, this cap in turn engaging the

adjustable jaw. The movements of the adjustable jaw 3 to clamp and release the pressure upon a line of matrices and spacers are effected by rotation of the screw 7 in reverse directions, the necessary rotary movements being imparted to the screw at appropriate intervals. In the present instance, the arm 13 is provided for the purpose of rotating the screw 7, this arm being connected to an actuating rod 14. The arm 14 has a loose fit on the adjusting rod, or member 6 and it abuts against the inner side of the bearing or guide 5 to sustain the thrust of the screw.

In setting the screw to conform to the different adjustments of the vise, the adjusting member or rod 6 is shifted axially or longitudinally with respect to the guide or bearing 5 and the actuating arm 13 and for this reason the arm 13 is provided with means for detachably connecting it to the rod or member 6 whereby these adjustments may be made. In the present instance, one side of the rod or member 6 is formed with a set of notches 15 which are spaced at graduated distances longitudinally of the rod, the spacing of these notches corresponding to the different set adjustments for the vise, and a key 16 is provided which is adapted to coöperate with any one of these notches to lock the arm 13 to the rod 6 so that the latter will rotate in unison with the rotary movements of the arm and the arm 13 will also sustain the axial thrust of the screw 7. This key is slideable in a groove 17 which is formed in one side of the arm 13 by the lateral flange 18, the key having a longitudinal slot 19 through which a screw 20 passes, this screw being carried by the arm 13 and it is provided on its outer end with a thumb nut or equivalent device 21 which is adapted to clamp the key in locked position. A handle 22 is preferably formed on the outer end of the key to facilitate manipulation thereof. When the key is retracted, the rod or member 6 is free to be shifted axially or longitudinally through the arm 13 and the guide or bearing 5, and the adjustment may then be set quickly and easily, according to the length of the line upon which the vise is to operate. To facilitate setting of the adjustment, a graduated scale 23 is preferably provided on the outer end of the adjustable rod or member 6. After the rod or member has been appropriately set, the key is returned to locking position and the arm 13 is then keyed to the rod or member 6 so that the latter is held from axial movement and it rotates in unison with the rocking movements imparted to the arm 13, the rotary movements of the rod or member 6 causing corresponding movements of the screw 7 and the latter operating upon the abutment 8 will cause the sliding vise jaw 3 to move periodically to-

ward the opposed vise jaw 2. In practice, the spacer pin 10 may directly engage the slideable vise jaw where the regular or standard adjustments are made, and the cap 12 may be applied to this pin to provide for intermediate adjustments. As the member 6 performs the dual function of operating the vise jaw and of providing for the different adjustments thereof, lost motion between the parts is minimized and the vise operates with certainty to clamp and release the matrices. Moreover, the different adjustments can be made quickly and easily, and as the different adjustments are indicated, there is no danger of the operator making an incorrect adjustment.

I claim as my invention:—

1. In a machine of the linotype class, vise mechanism embodying an abutment to co-operate with the movable vise jaw, a combined jaw-operating and adjusting member coöperative with said abutment, means for rotating said member, and a device for adjustably attaching said means to said member at different points in the length of said member.

2. In a machine of the linotype class, vise mechanism embodying a movable jaw, an abutment coöperative therewith, an actuating member for said jaw, and an operating screw having a threaded engagement with said abutment and adjustable axially relatively to said actuating member.

3. In a machine of the linotype class, vise mechanism embodying a movable jaw, an abutment therefor, an actuating member for said jaw, an operating screw having a threaded engagement with said abutment, and means to adjust said abutment and screw bodily relatively to the actuating member in a direction axially of the screw.

4. In a machine of the linotype class, a vise embodying a movable abutment for one of the jaws thereof, an operating screw having a threaded engagement with the abutment, and actuating means coöperative with the screw and having a device to hold the actuating means in different positions of adjustment with respect to the length of the screw.

5. In a machine of the linotype class, vise mechanism embodying an abutment to co-operate with the movable vise jaw, a rotatable member having a threaded engagement with said abutment and provided with axially graduated points, and means whereby the rotatable member may be set in different operative positions in the direction of its axis to correspond with said axially graduated points.

6. In a linotype machine, vise mechanism embodying a member having an operating connection with the movable jaw, and an actuating device having means for connecting it in different adjusted relations axially

of said member, and for rotating the latter to shift the movable jaw.

7. In a linotype machine, vise mechanism embodying an abutment to coöperate with the movable vise jaw, a member having a screw operatively engaging said abutment, and an operating arm having means for connecting it to said member at different points in the length thereof and operative to rotate said member to shift the movable jaw.

8. In a linotype machine, vise mechanism embodying an abutment to coöperate with the movable vise jaw, a member having a screw operatively engaging said abutment

and having graduated notches spaced axially thereof, a guide adjustably supporting said member, and an actuating arm abutting against said guide and having a key adapted to engage any one of said notches to lock 20 said arm to said member in different positions axially thereon.

In testimony whereof I have hereunto set my hand in presence of two subscribing witnesses,

WILLIAM E. BERTRAM.
